UNITED STATES PATENT OFFICE.

ALBERT S. REAVIS, OF WASHINGTON, DISTRICT OF COLUMBIA.

CONCRETE BUILDING CONSTRUCTION.

No. 843,768.

Specification of Letters Patent.

Patented Feb. 12, 1907.

Application filed October 29, 1906. Serial No. 341,110.

To all whom it may concern:

Be it known that I, ALBERT S. REAVIS, a citizen of the United States, residing at Washington, in the District of Columbia, have invented a certain new and useful Concrete Building Construction, of which the following is a specification, reference being had therein to the accompanying drawings.

10 This invention relates to concrete building construction, the object of the invention being to provide a bar of novel and effective construction adapted to be used as a core to be embedded in the concrete, which bar 15 when the concrete has hardened around the same will prevent slippage of the concrete lengthwise thereof should said concrete for any reason become loose upon the bar from jar or vibration or other cause.

20 With the above and other objects in view the invention consists in the novel construction, combination, and arrangement of parts herein fully described, illustrated, and claimed.

In the accompanying drawings, Figure 1 25 is a longitudinal sectional view of the bar of this invention shown embedded in concrete. Fig. 2 is an enlarged plan view of a portion of the bar. Fig. 3 is a cross-section through the same. Fig. 4 is also a cross-section showing a slight modification in the 30 form of the bar. Fig. 5 is a plan view similar to Fig. 2, showing a modified arrangement of ribs or transverse corrugations.

The bar contemplated in this invention 35 embodies a solid body 1, which is preferably equilateral or square in cross-section, as shown in Figs. 3 and 4, and provided with longitudinal ribs 2, which under the preferred embodiment of the invention are 40 located at and extend along the corners of the body. These longitudinal ribs 2 may be either parallel-sided, as shown in Fig. 3, with the opposite sides extending obliquely with relation to the opposite flat sides of the 45 body 1, such oblique and parallel-sided faces being designated at 3, or said ribs may be made heavier, as shown in Fig. 4, by making each of said ribs substantially square in 50 cross-section, the inner corners of the ribs merging into the corresponding outer corners of the square body of the bar.

Under either arrangement of ribs just described the bar is provided with channels 4, extending lengthwise of each of its sides, 55 said channels being defined and bounded at opposite sides by the ribs 2. Each of the

channels 4 is interrupted by any desired number of ribs or corrugations 5, which extend transversely across the channels, and these cross-ribs have flat parallel opposite 60 sides, as best shown in Fig. 1, in order to form square shoulders, against which the concrete hardens, after which it is impossible for the concrete to slip in a direction lengthwise of the bar, each and all of the cross- 65 ribs assisting in so holding the concrete.

The cross-ribs may be arranged at very frequent intervals or close together, as shown in Figs. 1 and 2, or said ribs may be located at greater distance apart, as indicated in Fig. 5. Also said ribs may be quite wide, as shown in Figs. 1 and 2, or narrow and thin, as indicated in Fig. 5. The cross-ribs on one side may either be arranged in transverse alinement with those on the remaining sides, as in Fig. 1, or they may be staggered, as indicated in Fig. 5.

The longitudinal ribs 2 obtain a firm hold upon the concrete and prevent relative turning between the concrete and the bar, while 80 the cross-ribs prevent endwise slipping between the same elements. Ordinarily these bars are made of steel; but of course any desired material may be used in their manufacture.

I claim—

1. A bar adapted to be used as a core to be embedded in concrete, comprising a solid flat-sided body angular in cross-section, a series of straight ribs extending lengthwise 90 of the body along the angles or corners thereof, and short transverse ribs extending at right angles to the longitudinal ribs, said short ribs crossing the flat sides of the body and interrupting the channels formed by the 95 longitudinal ribs.

2. A bar adapted to be used as a core to be embedded in concrete, comprising a square body, ribs extending lengthwise of the body and located at the corners of the body, and cross-ribs extending at right angles to the longitudinal ribs crossing and interrupting the channels left between the longitudinal ribs, said cross-ribs projecting outward beyond the outer ends of the longitudinal ribs.

In testimony whereof I affix my signature in presence of two witnesses.

ALBERT S. REAVIS.
